UNITED STATES PATENT OFFICE.

JOHN M. SCOTT, OF RACINE, WISCONSIN, ASSIGNOR, BY MESNE ASSIGNMENTS, TO OTTO R. BARNETT, OF CHICAGO, ILLINOIS.

RAIL-ANCHOR.

No. 909,892.

Specification of Letters Patent.

Patented Jan. 12, 1909.

Application filed March 10, 1904. Serial No. 197,477.

To all whom it may concern:

Be it known that I, JOHN M. SCOTT, a citizen of the United States, residing at Racine, in the county of Racine and State of Wisconsin, have invented certain new and useful Improvements in Rail-Anchors, of which the following is a specification, reference being had to the accompanying drawing, forming a part thereof.

10 The main object of my invention is to provide a rail-anchor of simple construction applicable to rails of different sizes, and adapted to prevent the longitudinal movement or creeping of the rails upon the ties, 15 while by a slight variation in its construction and application, it will serve also to prevent the spreading of the rails.

The invention consists in the peculiar construction and arrangement of parts as hereinafter particularly described and defined in the claims.

In the accompanying drawing, like letters designate the same parts in the several figures.

25 Figure 1 is a cross-section of two railway rails fitted with anchors of my construction, the anchor at the right being shown in elevation and the anchor at the left in section. Fig. 2 is a plan view of the same, the rail and anchor at the left being shown in horizontal section. Fig. 3 is a side elevation of the anchor as applied to a railway rail and tie, the rail being shown in side elevation and the tie in cross-section, and Fig. 4 is an 35 elevation of the inner side of one of the jaws.

Referring to the drawing, *a a* designate a pair of railway rails and *b* a tie upon which they rest. The anchor constituting my invention is composed of a pair of similar jaws *c c* which are formed with longitudinal recesses to receive the edges of a rail base or flange and with transverse horizontal bearings fitted against the bottom of the rail 45 base; and are adjustably connected by a threaded bolt *d* passing under the rail and through transverse holes in the jaws. These jaws are preferably made of malleable iron and are formed at one end with transverse 50 vertical bearing faces *e e* which are adapted to abut against one side of a tie as shown in Figs. 2 and 3. Hardened toothed bits *f f* are preferably inserted in the recesses of the jaws to afford a more secure hold upon

the base flanges of the rails as shown in 55 Figs 2 and 4. These bits are held in place by bending over them lips *g g* which are formed on the jaws at the ends of said recesses. Each pair of jaws may be clamped to a rail by a short bolt or two pairs may 60 be connected by a long bolt, as shown, to tie the rails together and prevent their spreading. In case of their application to the rails in independent pairs ordinary bolts having heads at one end and threaded and provided 65 with nuts at the other end are used.

In case of their application in connected pairs long bolts or tie rods threaded at each end for a distance somewhat greater than the width of the rail base and provided 70 with two nuts *h h* are used as shown in Figs. 1 and 2. In this way the spreading as well as the creeping or longitudinal displacement of the rails, is prevented.

In the application of the anchors to rails 75 of a track in either of the ways above mentioned, the jaws are placed on opposite sides of each rail with their bearing faces *e e* against the sides of ties opposed to the direction in which the rails tend to creep and are 80 tightly clamped upon the base flanges by turning up the nuts on the connecting bolts, the teeth of the bits *f f* being embedded more or less in the edges of the flanges and thus preventing any possibility of the rails slipping endwise in the jaws. The faces *e e* on both jaws of each pair afford an extended bearing which is disposed on both sides of each rail and effectively prevents the longitudinal displacement of the anchor and rail. 90

By providing bolts of sufficient length threaded a sufficient distance the same jaws may be readily and effectively applied to rails of different sizes, or rails having bases of different widths. 95

The jaws are made right and left but otherwise exactly correspond so that broken or imperfect parts can be readily replaced.

Various changes in details of construction may be made without departing from the 100 principle and intended scope of my invention.

I claim:

1. A rail anchor comprising a pair of separate jaws and a bolt adjustably connecting 105 the same and adapted to clamp them out of contact with each other upon a rail, one of the jaws having a bearing adapted to abut

against the side of a tie, substantially as described.

2. A rail anchor comprising a pair of jaws adapted to engage with the flanges of a rail base, and a bolt passing through and adjustably connecting the jaws below the rail and adapted to clamp them thereon out of contact with each other, one of the jaws having a depending bearing adapted to abut 10 against the side of a tie, substantially as described.

3. A rail anchor composed of a pair of jaws adapted to grip the flanges of a rail base and having bearing faces adapted to 15 abut against a tie, and a bolt adjustably connecting the jaws and adapted to clamp them out of contact with each other upon the rail base, substantially as described.

4. A railway-rail stay consisting of two 20 separate rail-gripping jaws fulcrumed on the rail-flanges and with horizontally-pro-

longed bottom bearings sustained out of contact with each other and abutting the side of the tie, lugs projecting from said bottom bearings, and a bolt engaging the lugs and 25 provided with means for drawing the jaws into engagement with the rail as set forth.

5. A railway-rail stay consisting of separate laterally-movable rail-gripping jaws, each formed with a bottom portion bearing 30 on the under side of the rail and with a depending lug, a bolt passing through the lugs and provided with a head on one end and with a nut on the opposite end, and an abutment depending from the bottom bearing 35 of one of the jaws as set forth and shown.

In witness whereof, I hereto affix my signature in presence of two witnesses.

JOHN M. SCOTT.

Witnesses:

WILLIAM A. WALKER,
G. N. FRATT.
